CLAIM

The ornamental design for a specimen substrate as shown and described.

DESCRIPTION

FIG. 1 is a perspective view of a specimen substrate, showing my new design;
FIG. 2 is a top view thereof;
FIG. 3 is a bottom view thereof;
FIG. 4 is a front view thereof; the rear being a mirror image;
FIG. 5 is a right side view thereof; the left side being a mirror image;
FIG. 6 is a top view of detail "6" identified in FIG. 2, shown enlarged for clarity of disclosure; and,
FIG. 7 is a top view of detail "7" identified in FIG. 6, shown enlarged for clarity of disclosure.
The oblique lines represent a transparent or translucent surface.
The broken lines showing elements in the above described Figures are for illustrative purposes only and form no part of the claimed design.
